UNITED STATES PATENT OFFICE

VERNON D. SPEER, OF CEDAR FALLS, IOWA

AEROPLANE ENGINE

Application filed November 25, 1929. Serial No. 409,604.

My invention pertains to internal combustion engines, and the object of my improvement is to supply particularly for aeroplane motors of this type, means for actuating both 5 the inlet- and the exhaust-valves of an engine in coordinated alternation with each other and in a suitable cooperation with other like devices of a block of plural cylinders using a single crank-shaft driven thereby.

10 This object I have achieved by the mechanism which is hereinafter described and claimed, and which is illustrated in the accompanying drawings, in which Fig. 1 is a central longitudinal section taken through 15 a plural engine block and particularly through one of the fixed radial cylinders thereof, parts being broken away. Fig. 2 is an elevation of one of the cylinders and of the operating connections for the exhaust- 20 valve as driven by a cam device, some of the elements intermediate for operating the inlet-valve being omitted, and some elements being shown in section or broken away. Fig. 25 3 is a plan view of the outer face of the inner yoke of the exhaust-valve operating means, with parts in cross section.

My invention is not restricted to the precise construction and arrangement of parts herein shown and described, nor to the various 30 details thereof, as the same may be modified or rearranged without departing from the spirit and scope of my invention, one practical embodiment of which has been herein illustrated and described without attempting 35 to show all of the various forms and modifications in which my invention might be embodied.

My invention also may be employed with any necessary modifications to effect the 40 above objects on any kind of internal combustion motor where the invention may be serviceable.

As illustrated, the invention is applied to a plural cylinder motor of said class where 45 the cylinders 9 are arranged in equidistantly spaced relation radially around a crank-shaft 6, which may as shown be the propeller shaft for an aeroplane motor.

The propeller shaft 6 has a crank 7, and 50 is positioned centrally in the engine block 1

which has a desired number of openings or cylindrical parts placed in registration therewith around with the cylinders 9 of which but one is shown. The piston 10 of the cylinder 9 has a piston-rod 8 with a roller-bearing connection to the crank-shaft crank 7. In the cylinder-head are positioned the ports 11 and 37 for the exhaust-valve 13 and the inlet-valve 36 respectively, the valves respectively opening inwardly and outwardly, the inlet-port in controlled communication with a chamber 42 leading into the combustion-chamber of said cylinder and with a conduit 40 leading from an annular supply-chamber 41 receiving gaseous fuel from a carburetor. 55 The exhaust-valve 13 controls the passage by way of the port 11 leading into an exhaust-passage 43, and the outwardly directed stem 14 of the exhaust-valve is reciprocatingly seated in a bearing projection 12 being part 60 of the cylinder-head, the stem emerging outwardly therefrom and terminally abutting upon the inner end of an adjusting-bolt 19 in a cup-shaped cap 18 having an adjusting-nut 17. The stem 14 within said cap is 65 encircled by a flanged washer 16 and by a coiled compression spring 15 engaged between the cylinder-head and said washer.

The inlet-valve 36 within the chamber 42 has a depending stem 35 mounted for reciprocation in an apertured bearing part 38 of the engine block which projects within the block and is surrounded by a compression-spring 39 whose inner end bears against the outer face of a washer 34 having oppositely 80 projecting annular flanges. The numeral 27 denotes a cam mounted on ball-bearings around a cylindrical part of the engine-block and being fixed to an internal-gear wheel 46 secured on the crank-shaft 6 to rotate therewith. A plunger-body 22 is mounted to reciprocate in a bearing in the engine block and has a forked inner extension 24 in which a roller 26 is pivoted at 25 to contact with the circumferential periphery of the cam 27. A rock-arm 23 has a diminished end inserted in said fork 24 above the roller 26 and has its other end forked to receive on a pintle thereacross a roller which at times engages 85 90 95

the edge of said cam 27, and the rock-arm is medially pivoted at 23'.

A yoke 28 (see Figs. 2 and 3) has spaced side members which converge toward their ends and there terminate in sockets 30 in which are rigidly seated the outwardly divergent arms 20. The inner walls of the said side members are flat and parallel at the middle and the opposite sides of the plunger-body 22 are flattened to fit slidingly between them as shown in said Fig. 3.

The outer ends of the members 20 are adjustably mounted in sockets 44 on the ends of an outer yoke 45 of reversed V-shape whose middle part is rigidly connected to said cup-shaped body 18, the members 20 being inclined relative to the cylinder 9 whose upper part traverses their widened interspace. The yoke 28 has curvate ledges 29 on the outer faces of its side members and a light compression spring 33 is engaged between said ledges and the under or inner face of the rimmed washer 34. An adjusting-screw 32 is mounted in the top of the plunger-body 22 and bears upon the inner face of the washer 34. The spring 33 is lighter than the spring 39. Inner ledges 28' on the yoke 28 are below lugs 22' on the plunger-body 22 in the paths of their downward movement.

As hereinbefore stated, the above described invention of mechanism between the cam 27 and the exhaust-valve 13 and the inlet-valve 36 respectively may be employed on any description of internal combustion engine for which they are suited, but this mechanism is particularly applicable to an aeroplane motor of the type shown, where the propeller shaft 6 mounted in roller-bearings or otherwise has a sleeve 4 secured terminally thereon bearing propeller blades shown broken away near the sleeve at 5.

My invention functions as follows: The cam 27 propels outwardly the plunger-body 22 which moves through the yoke 28 until the adjusting-screw 32 contacts with and propels outwardly the stem 35 to open the inlet-valve 37, compressing the spring 39. The exhaust-valve 13 being closed, as the cam rotates, the light spring 33 is allowed to extend to take up for any lost motion or looseness of the parts.

The cam projection 27' functions by contacting with the end roller on a rock-arm 23 medially pivoted at 23', and having its other and diminished termination inserted in the interspace of the furcations 24 of the plunger 22 to rock said arm and cause its said termination to engage inner shoulders on the furcations shown in Fig. 1 to pull down said plunger, which closes the inlet-valve 36 and also shifts downwardly the stem 20 to open the exhaust-valve 13, while placing the spring 15 under compression. It is to be understood that the washer 34 is rigidly mounted on the valve-stem 35, and that the screw 32 is below

and not connected to said stem and washer, so that there is a gap left between the screw 32 and the lower end of the valve-stem 35 when the body 22 moves down in following the peripheral edge of the cam 27, while keeping the roller 26 in contact with the cam edge for the requisite length of time before the actions of the valves are reversed. The adjusting-screw 32 may be used to adjustably vary the lead, as is evident.

Having described my invention, what I claim as new, and desire to secure by Letters Patent, is:

1. In an internal combustion engine, a cylinder having a head provided with an inlet-port and an exhaust-port and bearing apertures alined therewith, resiliently controlled valves for said ports, said valves having stems mounted in said apertures and directed in opposite directions, a crank-shaft, a piston in said cylinder operatively connected to said crank-shaft, a cam operatively mounted on said shaft, a plunger-body mounted for reciprocation in alinement with the inlet-valve stem and bearing terminally upon the circumferential periphery of said cam, and elements including a relatively light resilient device loosely connected between the other end of said plunger-body and said inlet-valve and exhaust-valve respectively and operative during a to and fro movement of the plunger-body to alternately open and then close said valves at determined intervals.

2. In an internal combustion engine, a cylinder having a head provided with an inlet-port and an exhaust-port and bearing apertures alined therewith, resiliently controlled valves for said ports, said valves having stems mounted in said apertures and directed in opposite directions, a crank-shaft, a piston in said cylinder operatively connected to said crank-shaft, a cam operatively mounted on said shaft, a plunger-body mounted for reciprocation in alinement with said inlet-valve stem and bearing terminally upon the circumferential periphery of said cam, and elements, including one mounted for longitudinal adjustments relative to the plunger-body and another having a light degree of resilience, loosely connected between the plunger-body and the inlet-valve and the exhaust-valve respectively and operative during to and fro movements of the plunger-body to alternately open and close said valves with an adjustably determined relative lead.

3. In an internal combustion engine having both inlet- and exhaust-ports, resiliently controlled valves for said ports movable in opposite directions to close the ports, a reciprocable body, means for reciprocating said body, said body being mounted adjacent the inlet-valve, an adjustable element mounted on said body between it and said valve in a gap therebetween whereby in one movement

of said body said element traverses said gap to impinge upon and thrust open said inlet-valve, an elastic element lighter than the resilient controlling means for said valves contacting with the inlet-valve and positioned between the latter and the abutting part of said body, an apertured yoke through which said body is slidably mounted with said elastic element contacting with said yoke, and operative connections between the ends of said yoke and the outer part of the exhaust-valve, whereby the said body during to and fro movements actuate said valves with a desired adjustable lead in alternation.

4. In an internal combustion engine having both inlet- and exhaust-ports, resiliently controlled valves for said ports openable in opposite directions, and connected devices mounted for to and fro movements including relatively light resilient means and adjusting means, said devices being operative upon said valves in alternation to open and close them with an adjustably determined relative lead.

5. In an internal combustion engine having a cylinder with inlet- and exhaust-ports in one end, valves resiliently controlled to open and close said ports, a yoke having a medial resilient connection to the exhaust-valve and crossing the cylinder-head, a reciprocable yoke crossing one side of the cylinder, a relatively light elastic body engaged between the medial part of said latter yoke and the inlet-valve, an element movable to and from said valve to propel it to open position while moving in one direction and to separate by a gap therebetween while returning in the opposite direction, and side rods rigidly and adjustably connected between the ends of said yokes without said cylinder for actuating the exhaust-valve.

6. In an internal combustion engine, a cylinder having a head provided with an inlet-port and an exhaust-port and bearing apertures alined therewith, resiliently controlled valves for said ports having stems mounted in said apertures and oppositely directed, a crank-shaft, a piston in said cylinder operatively connected to said crank-shaft, a cam operatively mounted on said shaft having separated projecting edge parts, a plunger-body mounted for reciprocation in alinement with the inlet-valve stem to bear terminally upon the peripheral edge of the cam, a rock-arm medially pivoted with one end movably engaged with said plunger-body and the other end free to be engaged by one of the cam projections and rocked to move the plunger-body in one direction to cause the plunger-body to close said inlet-valve, and connected elements including a resilient device loosely connected between the other end of the plunger-body and said inlet- and exhaust-valves respectively, whereby the projections of said cam operate to alternately

open and close said valves at determined intervals.

7. In an internal combustion engine, a cylinder having a head provided with an inlet-port and an exhaust-port and bearing apertures alined therewith, resiliently controlled valves for said ports having stems mounted in said apertures and oppositely directed, a crank-shaft, a piston in said cylinder operatively connected to said crank-shaft, a cam operatively mounted on said shaft and having separated projecting edge parts, a plunger-body mounted for reciprocation in alinement with the inlet-valve stem to bear terminally upon the peripheral edge of the cam, a rock-arm mounted for rocking movements to have one end engage said plunger-body and its other end free and positioned to be engaged and rocked by one of the cam edge projections to shift the plunger-body to close said inlet-valve, and connected elements loosely connected between said inlet- and exhaust-valves, their stems and said plunger body angularly, including an adjusting screw operable to vary the lead of the valves, and resilient means to cooperate therewith, whereby the separated cam projections act upon the inlet- and exhaust-valves in succession in opening and closing them with an adjusted variation of lead.

In testimony whereof I affix my signature.
